UNITED STATES PATENT OFFICE.

JOHN J. DAVIS, OF WATERVILLE, CONNECTICUT, ASSIGNOR OF ONE-HALF TO ELVIRA M. CLARK, OF WATERVILLE, CONNECTICUT.

STAMP-HOLDER.

1,014,380.

Specification of Letters Patent.

Patented Jan. 9, 1912.

Application filed November 1, 1911. Serial No. 658,035.

To all whom it may concern:

Be it known that I, JOHN J. DAVIS, a citizen of the United States, residing at Water-ville, in the county of New Haven and State 5 of Connecticut, have invented a new and useful Improvement in Stamp-Holders; and I do hereby declare the following, when taken in connection with the accompanying drawings and the letters of reference 10 marked thereon, to be a full, clear, and exact description of the same, and which said drawings constitute part of this specification, and represent, in—

Figure 1 a side view of a stamp holder 15 constructed in accordance with my invention. Fig. 2 a side view of the same, with the caps removed. Fig. 3 a longitudinal sectional view on an enlarged scale. Fig. 4 a sectional view on the line *a—b* of Fig. 2, on 20 an enlarged scale. Fig. 5 a similar view showing one end of the strip contained in the holder, projecting outward through the slot.

This invention relates to an improvement 25 in stamp holders, the object being to provide a convenient receptacle formed from sheet metal to contain stamps and from which the stamps may be conveniently delivered; and the invention consists in the construction 30 hereinafter described and particularly re-cited in the claims.

In carrying out my invention, I employ a casing 2 preferably formed from a piece of tubing of desired diameter around the center 35 of which is a band 3 which may be formed integral with the tube and applied thereto, and which forms shoulders 4, 5. The ends 40 of the tube are formed with slots 6 and 7 one edge of which is turned inward to form an inwardly projecting lip 8. As herein shown 45 a plug 9 is inserted into the center of the tube to separate the ends and so as to form chambers 10 and 11. These chambers are less in depth than the width of the strip to be contained therein. The chambers are 50 closed by caps 12 which closely fit the tubular portion and which come to a bearing against the shoulders 4 and 5. A roll of stamps 13 is inserted into each of the chambers which, as before stated, are less in

depth than the width of the roll of stamps so that the stamps project beyond the ends of the tubes. When it is desired to remove a stamp the cap is removed and the roll of stamps turned in proper direction to cause 55 the end of the strip to engage with the lip 8 and pass through the slots 6 or 7. When the desired number of stamps is withdrawn, a strip may be conveniently cut against the opposite edge of the slot in the casing. If 60 more stamps are drawn off than required, by turning the roll in the opposite direction they will be wound upon themselves in the chamber.

This device forms a convenient receptacle 65 for stamps and similar articles so that they may be conveniently carried in the pocket, and protects the stamps at all times against moisture.

I claim:—

1. A stamp holder comprising a tubular casing forming chambers at opposite ends, said chambers longitudinally slotted, and one edge of the slot turned inward the depth of the chamber being less than the 75 width of the strip to be contained therein, and caps adapted to set over and inclose said chamber.

2. A stamp holder comprising a tubular casing, a central plug within the same and 80 forming chambers at opposite ends, said chambers being less in depth than the strips to be contained therein, said chambers formed with longitudinal slots, one edge of each slot turned inward, and caps adapted 85 to set over and inclose said chamber and inclose said slots.

3. A stamp holder including a tubular chamber formed with a slot, the depth of the chamber being less than the strip of stamps 90 to be contained therein, one edge of the slot turned inward, and a cap adapted to set over and close said chamber.

In testimony whereof, I have signed this specification in the presence of two subscr- 95 ing witnesses.

JOHN J. DAVIS.
